UNITED STATES PATENT OFFICE.

THEODORE T. WOODRUFF, OF ALTON, ILLINOIS.

IMPROVEMENT IN RAILROAD-CAR SEATS AND COUCHES.

Specification forming part of Letters Patent No. **16,159**, dated December 2, 1856.

To all whom it may concern:

Be it known that I, THEODORE T. WOODRUFF, of Alton, in the State of Illinois, have invented certain new and useful Improvements in Convertible Seats and Couches for Railroad-Cars; and I do hereby declare that the following is a full, clear, and exact description, reference being had to the accompanying drawings, making part of this specification, in which—

Figure 1 is a central longitudinal vertical section of a portion of a railroad-car, representing the convertible seats and couches in elevation; Fig. 2, a cross vertical section of a car, taken at the line A a of Fig. 1, and representing the seats on one side of the car and the seats converted to couches on the other side; and Fig. 3, a section representing a modification.

The same letters indicate like parts in all the figures.

My said invention relates to improvements of a prior invention for this purpose for which I filed an application for Letters Patent on the 6th day of August, 1856; and the first part of my present invention consists of a certain combination by which the four seats—two at each end—in each of a series of compartments on each side of the car may be converted to form two depressed couches; and the second part of my said invention consists in combining the hinged backs of any two opposite seats of each compartment to form an elevated couch above the couch formed by the seats to which the said backs belong; and the last part of my said invention consists in combining two sets of hinged cushioned frames, one set at each end of each compartment, each of the said sets consisting of two frames hinged to each other, and one of them, in turn, hinged to one of the partitions forming the compartment, by means of which combination each set of frames may be folded up out of the way, and when required to be used as a couch the two sets may be unfolded and connected in a horizontal position to form a couch.

In the accompanying drawings, *a* represents the floor of the car; *b b*, the sides; *c*, the roof, and *d* the windows, all of which may be of the usual construction. There is to be the usual longitudinal passage-way, *e*, between the ranges of seats, bounded on each side by the end frames, *f*, of the seats, formed in the usual manner with arm-supports. The space on each

side between the sides of the car and the central passage-way is to be divided into compartments *g g* by cross vertical partitions *h h*, extending up from the floor to about the usual height of the backs of the seats, although they may be extended up to any other suitable height, and even to the roof, if desired. In each compartment there are four permanent cushion-frames, *i i i*, two side by side against each partition *h*, but lower than the usual height of car-seats—say about half the height, more or less; and in front of each of these frames there is another and movable cushioned frame, *j*, of about the same size, and hinged thereto by two metal straps or links, *k k*, which are connected with said frames by a pin or equivalent joint near the front edge of the permanent frame *i* and near the back edge of the movable frame *j*, so that the movable frame may be thrown back and over the permanent frame, to form a seat, in the position *l*, or drawn forward and down to the level of the permanent frame, that the two, in connection with the corresponding two similarly arranged on the opposite side of the compartment, may form a low couch, as represented at *m m*. In this way the four movable frames can be made into four seats of the usual height, or, in connection with the four permanent frames, converted into two long couches for passengers to lie down.

The backs *n n n n* of the four seats are cushioned frames, connected at their upper ends by hinge-joints *o* with the partitions *h*, so that they can be let down in a nearly vertical position, as represented at *p*, or turned up in a horizontal position, as represented at *q*. To the lower and under edge of two of these backs is hinged another cushioned frame, *r*, of the same width, but shorter, the two being hinged, so that the frames *r* may be folded or turned up behind the backs, when placed in the position represented at *p*, to form a back for the seats, or turned out in the same plane with the back when placed in a horizontal position, as represented at *q*, to form an elevated couch, in connection with the corresponding frames on the opposite side. The backs of the two seats placed side by side may have their backs arranged in this manner with an additional frame, *r*, so as to form, in connection with the backs of the two opposite seats, two couches side by side; but instead of this the backs of the two opposite seats next to the side of the car may be made without the additional frame *r*, and

in that case there is to be an elevated cushioned frame, *t*, attached to and projecting from the side of the car on a level with the windows, to fill up the space between the two corresponding backs when thrown up in a horizontal position, to form, in connection with them, one of the elevated couches, as represented at *u*. When the backs are elevated to a horizontal position to form couches they are to be secured by catches and bolts in any suitable manner.

When the seats are to be converted into couches the frames which form the seats when in the position *l* are to be drawn out to the position *m m* to form couches, and then the backs can be converted into elevated couches; and when the couches are to be converted into seats the backs are first to be folded and then the frames elevated and carried back to the position *l*, to form the seats. Another elevated couch is formed above the windows in each compartment, in the sides of the car, by the combination of two sets of frames, each set being composed of two cushioned frames, *v w*, hinged together, as at *x*, so that they can be folded up, as represented at *y*, to be out of the way, the frame *v* being in turn hinged by the opposite edge to a partition, *z*, extending down from the roof and extending out from the side of the car; or these partitions may be continuations of the partitions *h h*. There are two such sets of hinged frames for each compartment, and when they are to be formed into an elevated couch they are folded out in a horizontal position, as represented at *a'*, the two sets uniting in the middle, and there secured in a suitable manner by catches or bolts. In this way five couches may be formed in each compartment, so that, if preferred, the four persons occupying the four seats of each compartment may be accommodated with couches without the necessity of using either the lowest couch nearest the side of the car or the couch formed by the backs of the two seats farthest from the side of the car; or, if desired, the three couches in each compartment nearest the side of the car may be used as such, leaving two seats next to the passage-way *e*.

The several frames above described may be made and cushioned in any suitable manner, as this makes no part of my invention; and the manner of forming the hinges by which they are connected with each other and with the partitions of the several compartments may be modified in any manner which will admit of folding and unfolding them in the manner substantially as described.

It should be desired to make the backs *n* of the seats low, or to elevate the couches formed by the backs to a greater height, this may be effected by forming the hinged joint, as represented in Fig. 3, with a projecting stem, *b'*, on each side of the back. In this way the couch will be elevated above the hinge-joint to the extent of the length of the stem.

I am aware that it has been proposed to convert the usual reversible backs of railroad-car

seats into couches by turning up the said reversible backs of two sets of seats in each compartment into a horizontal position and bringing the edges of two of them into contact and there securing them; but this is objectionable for the reason that in such case the backs so used, to give the required length of couch, would make the backs too high when used as backs, and, besides, both surfaces require to be cushioned, because the surface which is used as a back cannot constitute the couch; but by my invention the same cushioned surface is used both for the back and the couch, and without any necessity of making the backs of more than the usual height; and I am also aware that it has been proposed to convert the opposite seats of railroad-cars into couches by having each seat double with one of the cushioned frames to form the connection between any two of the seats; but this is objectionable for the reason that the seats so arranged can only be converted into couches when the backs are made on the plan known as "reversible backs," and for the further reason that when the seats are converted into couches they cannot be depressed sufficiently below the usual height of the seats to leave the required space between the lower couches and the second tier of couches when formed of backs of the usual and appropriate height; and, again, this method is objectionable for the further reason that if any of the seats in any one compartment are converted into couches all must be, so that the passengers in any one compartment must either all sit or all lie down, whereas on my plan some may lie down and others sit up, at their election.

What I claim as my invention, and desire to secure by Letters Patent, is—

1. The combination of the movable and fixed frames on one side of each compartment with the movable and fixed frames on the opposite side thereof, to form of each two depressed couches when unfolded and connected, and which may be converted into two opposite seats when the two movable seats are thrown up and over the permanent frames, substantially as described.

2. Combining each of the hinged folding backs on one side of each compartment with each of the corresponding hinged backs on the opposite side of the same compartment by means of the folding or connecting frames or equivalent therefor, substantially as described, whereby the same may be used as backs for the seats or as couches, as set forth.

3. Forming an elevated couch above the windows by the combination of the two sets of hinged frames, substantially as described, so that when not required to be used as a couch the two sets of frames may be folded up out of the way in the manner substantially as described.

T. T. WOODRUFF.
